UNITED STATES PATENT OFFICE.

CHARLES O. WILSON, OF CINCINNATI, OHIO.

IMPROVEMENT IN WATER CUT-OFFS.

Specification forming part of Letters Patent No. **179,246**, dated June 27, 1876; application filed February 29, 1876.

To all whom it may concern:

Be it known that I, CHARLES OSBORN WILSON, of Cincinnati, Hamilton county, Ohio, have invented a new and useful Attachment to Cut-Off Pipes; and do hereby declare the following to be a full, clear, and exact description of the construction and operation of the same, reference being made to the annexed drawing, in which—

Figures 1 and 3 represent the cut-off pipe in its two different positions, and Fig. 2 a transverse section of the pipe, A being the opening where the liquid comes in; B and C, the outlets for the liquid; D, the leading or cut-off pipe; G, the cap for the purpose of effectually turning the liquid; H H, the pivots in the leading or cut-off pipe on which the cap G turns; and F F, the pivotal handle or crank attached at I.

This attachment to a cut-off or leading pipe is to be operated by turning the little crank F F a half revolution, which turning on the point I and being firmly soldered to the cap G, and the cap G fastened by the pivots H H

to the leading or cut-off pipe, and turning upon them, the leading or cut-off pipe may be shifted over either outlet B or C, and the liquid so turned in either direction, and by means of my improvement the leading or cut-off pipe will be brought squarely over the outlet B or C, the communication between the two be completely cut off, and a perfect communication with one outlet, and a perfect non-communication with the other outlet, secured at the same time.

I disclaim everything except the cap G and combination of the handle or crank F F.

I claim as my invention and desire to secure by Letters Patent—

The cap G, in combination with the crank F F, so applied to the cut-off pipe as to bring the mouth of the pipe squarely over the outlet, and make the communication and non-communication with the outlets perfect.

CHARLES OSBORN WILSON.
